CLAIM

The ornamental design for an arm rest pillow, as shown and described.

DESCRIPTION

FIG. 1 is a top view of an arm rest pillow showing my new design.

FIG. 2 is a bottom view of the arm rest pillow.

FIG. 3 is an end view of the arm rest pillow.

FIG. 4 is a first side view of the arm rest pillow; and,

FIG. 5 is a second side view of the arm rest pillow.

The dashed line seen in the figure views is understood to represent stitching.
